TOY PLAYER PIANO

Howard N. Barnum, South Euclid, Ohio

Application April 3, 1947, Serial No. 739,055

18 Claims. (Cl. 84—97)

1

This invention relates to toy musical instruments, and has particular reference to a novel miniature player piano.

One of the objects of the invention is to provide, in a toy musical instrument or piano, an improved mechanism for mechanically reproducing a tune or piece of music by an action including the intermittent partial rotation, and alternate bodily oscillation at substantially right angles to the plane of rotation, of a disk having striker parts or projections arranged according to the tune to be played, and which, when said disk is so actuated by a crank action or other means, will, through cooperation with plungers or the like incorporated in the sound producing organism, result in the playing of said tune.

Another and related object is to so arrange or distribute the striker parts or projections on the disk, relative to the plungers or the like, as to effect compactness of structure which, in the case of a miniature piano, permits the use of a keyboard of usual length in such instruments, and the employment of a disk of minimum diameter.

Another object of the invention is to provide a toy piano incorporating the aforesaid mechanism and which will especially appeal to children because of its close resemblance to a large piano of corresponding style.

A further object is to provide a toy musical instrument, particularly in the nature of a miniature player piano, in which disks are employed for actuating the sound producing organism, and which disks are especially convenient of insertion and removal, such operation requiring only the depositing of the disk in a pocket or space provided for the purpose.

A still further object is to provide, in a toy piano of the above described character, a top section that normally covers the said space or pocket and that is capable of being swung open, in substantially the manner of an equivalent part of an ordinary piano, to afford access to said space or pocket.

With the above and other objects in view which will more fully appear as the nature of the invention is better understood, my improvements may be said to consist in the novel construction, combination and arrangement of parts herein-after described, illustrated and claimed.

One practical embodiment of the invention is shown in the accompanying drawings, in which:

Fig. 1 is a front elevational view of a toy piano embodying the invention;

Fig. 2 is a plan view, on a somewhat larger scale, with the top of the case omitted, showing the keys and their actuating plungers;

2

Fig. 3 is a rear elevational view, partly broken away, of the piano, showing the way in which the disk is supported for rotation, as well as the means for rotating and oscillating it;

5 Fig. 4 is a sectional view on line 4—4 of Fig. 2;

Fig. 5 represents a vertical section through the piano on the line 5—5 of Fig. 2;

10 Fig. 6 is a front elevational view of a type of disk having projections for actuating the plungers of the sound producing organism, being the form shown in the previous views wherein the disk appears;

15 Fig. 7 is a fragmentary front elevational view of a modified form of the disk in which voids in the form of radial slots provide clearance for the plungers that are to remain inactive, and which has striker parts that bridge said voids or slots for actuating the plungers required for the playing of a selected tune, and

20 Fig. 8 is a fragmentary vertical sectional view of one of the pivoted keys and its actuating plunger, showing the parts in normal position in full lines, and in sound producing position in dotted lines, in which latter position the plunger is engaged by one of the striker parts of the modified form of disk.

Similar reference numerals designate corresponding parts throughout the several views.

In carrying the present invention into effect, it 30 is proposed to provide a casing which includes opposite side walls 10 and 11, respectively, a pivoted back wall 12 that constitutes the sounding board, a top 13, and a key board 14, the latter extending horizontally across the front of the piano and connected securely to the side walls 10 and 11. These side walls and top are preferably shaped to simulate an upright piano of usual style, and it is particularly important to do so as it enhances its esthetic characteristics

35 in child appeal. While only one octave of keys 15 is employed in the piano illustrated in the drawings in order to insure compactness and minimize cost, it should be understood that additional ones may be added within reasonable limits without affecting the merits of the invention.

40 A front, vertical wall 16 is inset from the front plane of the piano and is suitably attached at its ends to the side walls 10 and 11, and adjacent its lower edge to a bottom 17. The front wall 16 terminates at its upper edge slightly below the horizontal plane of the key board 14. By this arrangement of the walls, sufficient space is provided to accommodate the various operating parts of the sound producing organism.

45 55 One of the more important features of the invention resides in the use of a substantially flat

disk, shown in one form in Figs. 1, 2, 3, 5 and 6, where it is designated 19. The disk may be made from metal, plastic, or any other material that is sufficiently stiff and hard and will not warp to an appreciable extent. The disk 19 is provided with a plurality of striker parts or projections 20 arranged in a predetermined manner according to the tune that is to be played by the particular disk. The disk 19 is further provided with a plurality of peripheral notches 21, equally spaced apart, and through which, by cooperation with mechanism later to be described, the disk may be rotated with an intermittent or step by step movement.

As shown more clearly in Figs. 1, 2, 3 and 5, this disk 19 is suitably supported on the back wall 12 for rotation about an axis slightly to one side of the longitudinal center of the bank of keys 15. Positioned on the rear upper portion of the back wall 12, in parallel spaced relation thereto, is a flat member 25, which, with said wall, and blocks 27 and 28 that are disposed between said wall and the end portions of said member, define the space or pocket for the disk 19. Said disk is sustained, and biased toward the block 28, by an inclined support 29 that is carried by the back wall 12. It will be obvious, therefore, that the disk 19 may be inserted into this space or pocket and removed therefrom as desired, and when positioned in the space or pocket, it is free to rotate. With the arrangement described, it is not necessary to provide a pivotal support for the disk, which greatly facilitates and simplifies the emplacement and removal of the disk.

The sound producing equipment includes a heavy metal bar 33 that is positioned along the lower inner portion of the back wall 12 and securely connected to the latter by a plurality of bolts 34. Said bar is provided with round extensions 35 projecting in an axial direction from its upper forward corners. The extensions 35 are pivotally mounted in aligned bearings 36 on the side walls 10 and 11, thereby to afford pivotal movement of the assembly including said bar and the back wall 12. Due to the fact that said bearings 36 are well forward of the plane of the back wall, said assembly is biased by gravity to swing in a rearward direction, but is normally retained in a forward slightly inclined position by a stop 37 on the side wall 11 (Fig. 3).

The bar 33 is provided with a plurality of musical tone rods 38 which have their lower ends rigidly embedded in the bar and rise therefrom in parallel spaced relation to the back wall 12. There are eight such rods in the present instance, graduated in length to produce the tones of a musical scale. These rods are spaced apart similarly to the spacing of the keys 15, each rod being about central of a key.

The keys 15 are, as usual, in transverse alignment, and are pivoted for individual movement on a shaft 39 that is supported by and between the side walls 10 and 11, the end portions of said shaft beyond the bank of keys, passing through blocks 41. Tubular spacer members 42 may be disposed on the shaft between the end keys of the bank and the blocks 41. The keys may be considered, for the purpose of description, as arranged in two groups of four keys each, located on different sides of the center of the piano. Suitable means are provided for effecting the pivotal movement of each key and as this means is identical for each group, a detailed description

of one should therefore suffice. The keys 15 in the left-hand group will be explained.

A sheet metal strap 43 extends down one side, across the bottom, and up the other side of each key 15, about midway the length of the key, in a position to receive through apertures thereof the shaft 39. This provides durable metal bearings for the key. At one side the strap is extended above the key and thence laterally in one direction or the other to provide a bell crank lever 44. The bell crank 44 of the first or left hand key of the left hand group, as the parts are viewed in Figs. 1, 2 and 3, projects to the right across said key in parallel spaced relation thereto, almost the width of the key. The bell crank 44 of the second key also projects to the right a shorter distance across the key in parallel spaced relation to the upper surface. The bell crank of the third key projects to the left and overhangs the second key a short distance, while the bell crank of the fourth key extends to the left across the third key for nearly the width thereof. The straps and bell cranks of the right hand group of keys are identical with those of the left hand group, only they are reversed, and they are designated 43^a and 44^a, respectively. The bell cranks 44 and 44^a are normally in transverse alignment along and above the shaft 39 and each is formed with an opening 51. The openings 51 of the bell cranks of each group are substantially equally spaced apart, and due to the formation and arrangement of the bell cranks, they are quite close together.

Referring particularly to Fig. 5, each key 15 is provided with a hanger 52. Said hanger is rigid with the key and is disposed in perpendicular relation thereto. A resilient member 54 is carried by the wall 16 and acts as a silent stop to limit the forward swinging movement of the hanger. A simple and efficient hammer supporting means is employed and preferably consists of superimposed layers of cardboard or the like and a suitable fabric, adhesively connected together to provide a composite strip 55. This strip is relatively long and has its upper end portion secured to the inner face of the hanger 52 by fastening means 56. The aforesaid layer of cardboard or the like is severed transversely at 57 below said fastening means 56 to afford a hinge action, and the lower end of the strip 55 extends below the free end of the hanger. A circular hammer 58 of wood or other suitable material is rigidly connected to the lower end of said strip. It is obvious, therefore, that upon depression of the key 15 against a resilient silent stop 59 on the key board 14, said key will be rocked about its pivot constituted of the shaft 39, and move the hanger 52 to the rear, causing the hammer 58 to be swung in a corresponding direction. As the key is stopped as aforesaid, the strip 55, being hingedly mounted on the hanger 52, continues to move under its own inertia and strikes its respective tone bar 38, from which it immediately drops away so as not to dampen the vibration of the tone bar, which would interfere with its clear tone. It is understood, of course, that each key is a part of an assembly like the one above described, and that each such assembly is associated with one of the tone bars 38.

To operate these several key assemblies, I provide a like number of identical plungers 60. The rear ends of the plungers are shown as enlarged and as guided within holes in the back wall 12, while the front ends of the plungers are turned

downwardly and projected through the holes 50 of the bell cranks 44.

It follows from what has been said that there are two groups of four plungers each, and that they are substantially equally spaced apart transversely of the piano by reason of the spacing of the holes 50 of said bell cranks.

Now, when a disk 19 is placed within the space or pocket provided for its reception, it will dispose the striker parts or projections 20 of the disk in operative relation to the plungers 60. The striker parts or projections 20 are arranged in arcs or circles concentric with the axis of the disk, those intended for cooperation with the plungers 60 of the right hand group being intermediate the arcs or circles in which are arranged the striker parts or projections that are intended for cooperation with the plungers of the left hand group. By this arrangement, which accounts for the previously explained fact that the axis of rotation of the disk is slightly to one side of the center of the key bank, a more compact structure is made possible, as well as the use of disks of minimum diameter, for the reason that all of the plungers do not have to be on the same side of the center of rotation of the disk.

When the back wall is in its rear position against the stop 37, the rear ends of the plungers 60 repose within the holes in the back wall provided for their accommodation, as best shown in Fig. 5; but when said wall is swung forwardly by mechanism yet to be described, the plungers extend a substantial distance into the disk receiving space or pocket. Consequently, if a striker part or projection 20 of the disk is in line with a plunger at the time the wall 12 is swung forwardly, such part or projection will engage the plunger and urge it forwardly thereby to rock the corresponding key assembly, through the medium of its bell crank 44, to swing the corresponding hammer 58 against the appropriate tone bar 38. It is apparent, therefore, that, by alternate intermittent rotation and oscillation of the disk, different striker parts or projections will be brought into alignment with certain of the plungers and through them actuate the sound producing organism to cause the tune to be played which corresponds to the arrangement of striker parts or projections on the particular disk that is being used.

I shall now describe the mechanism for rotating the disk and oscillating the back wall 12, or, more accurately, the assembly of which it forms a part. Supported for rotation in bearings in the front wall 16 and back wall 12, at about the transverse center of the piano, is a shaft 65 which has a crank 66 secured to its forward end. To the rear end of the shaft is fastened a cross arm 67 which has a forwardly extending finger 68 at one end, and a cam engaging part or roller 69 at the other. The finger 68 is intended for engagement within the peripheral notches 21 of the disk 19, while the part or roller 69 cooperates with a cam member 70 on the wall 12. Said cam member is desirably made of rubber or the like to insure quiet operation. A spring 72 that surrounds the shaft 65 and is compressed between the crank 66 and the front wall 16, retains the shaft in a forward position with the cross arm 67 adjacent the wall 12 during the oscillatory movements of said wall, the spring being of such strength as to accomplish this purpose while, at the same time, permitting the relatively heavy assembly including the wall 12 to gravitate rearwardly against the stop 37.

I have already explained how the intermittent rotation and alternate oscillation of the disk actuates the sound producing organism to play a tune according to the arrangement of the striker parts or projections of the disk, and it will now be seen that this operation of the disk results from a turning of the crank 66. When the shaft 65 is rotated by means of the crank 66, the finger 68 will enter a peripheral notch of the disk and impart to the disk a partial rotation corresponding approximately to the spacing apart of the peripheral notches 21. Now while the disk remains in this position with one of its striker parts or projections in line with a plunger 60, the part or roller 69 will override the cam 70 and swing the back wall 12 and disk 19 forwardly to cause said striker part or projection to push the plunger forwardly and operate the corresponding key assembly. Thus, by continually rotating the crank, the tune represented by the particular disk will be played.

In the form of the disk illustrated in Fig. 6, the words and music are printed upon or otherwise applied to the front face of the disk, as shown in Fig. 6, where a musical staff occupies an annular space adjacent the edge of the disk, with the words arranged below the notes on the staff in conjunction with which they are to be sung. Consequently a child, playing the piano, may sing the song that is being played, thus becoming more familiar with the notes and words. By dropping the disk into the space or pocket with the musical clef at the top, the disk will be positioned for the starting of the tune when the crank is rotated.

If the disk 19 is made of plastic or the like, the projections 20 may be cast thereon; or if made of metal, they may be struck from the face of the disk, either as bosses, or as lugs partially severed from the material of the disk and turned up.

In Fig. 7 I have shown a disk 19^a wherein striker parts 20^a are formed by portions of the disk that bridge radial slots 75 which ordinarily permit the passage, through the plane of the disk, of the enlarged rear ends of the plungers 60^a, shown in Fig. 8. Here the back wall 12^a is provided with openings 50^a, the same as in the previously described form of the invention, for the accommodation of the rear ends of the plungers 60^a, while the member 25^a that is carried by the back wall has openings through which the rear ends of the plungers may extend when the back wall is swung forwardly. In this arrangement, as illustrated in the drawings, the words have been omitted from the disk. However, by making the disk larger; or, by moving the voids or slots nearer to the center of the disk, and correspondingly shifting the position of the plungers 60^a, both music and words may be included, as in the first described form.

Having thus described my invention, what I claim is:

1. In a musical instrument, the combination with a series of sound producing organisms, and a plurality of actuators for effecting the operation of said organisms; of a disk having striker parts arranged thereon according to a tune to be played and in circles substantially concentric with the axis of rotation of the disk, means supporting the disk in operative relation to said actuators, for rotation about said axis in a plane wherein the aforesaid striker parts escape the actuators, and for to-and-fro movement at substantially right angles to its plane of rotation so as to cause the striker parts to engage and operate the actuators, the actuators coinciding in

position with said circles when the disk is supported by said means, and mechanism for alternately imparting step-by-step rotation and to-and-fro movement to the disk.

2. The combination of elements recited by claim 1, wherein the actuators are arranged in groups on opposite sides of the axis of rotation of the disk, and the striker parts that are intended for cooperation with the actuators of one group lie in different circles from those occupied by the striker parts that are intended for cooperation with the actuators of the other group.

3. The combination of elements recited by claim 1, wherein the actuators are arranged in substantially horizontal alignment and are separated into two groups that lie, respectively, on opposite sides of the axis of rotation of the disk and in substantially the horizontal plane of said axis; and wherein the striker parts that are intended for cooperation with the actuators of the respective groups occupy alternate circles.

4. The combination of elements recited by claim 1, wherein the disk bears a musical staff that extends substantially circumferentially of the disk, and notes are associated with said staff representing the tune produced by virtue of the arrangement of the striker parts of the disk, the staff and notes bearing such relation to said striker parts that the notes are in readable position when the musical tones corresponding to the notes are sounded.

5. The combination of elements recited by claim 1, wherein the disk bears the words of a song, the tune of which is produced by virtue of the arrangement of the striker parts of said disk, the words bearing a given relation to said striker parts so that the words are in readable position when the musical notes corresponding thereto are sounded.

6. In a musical instrument, the combination with a series of sound producing organisms, and a plurality of actuators for effecting the operation of said organisms; of a disk having striker parts arranged thereon according to a tune to be played and in circles substantially concentric with the axis of rotation of the disk, means peripherally supporting the disk for rotation about said axis in a plane wherein the aforesaid striker parts escape the actuators and for to-and-fro movement at substantially right angles to its plane of rotation and in operative relation to said actuators so as to cause the striker parts to engage and operate the actuators, the actuators coinciding in position with said circles when the disk is supported by said means, and mechanism cooperating with circumferentially spaced peripheral portions of the disk for imparting step-by-step rotation to the disk, said mechanism acting also to impart to-and-fro movements to the disk that alternate with the step-by-step rotative movements thereof.

7. In a musical instrument, a revolvable disk having striker parts arranged in circles of different radii, a device adapted to support said disk for rotation and having a plurality of guides coinciding with the different circles for registration with successive striker parts as the disk is revolved; said device being pivotally mounted on an axis extending substantially parallel with the plane of the disk to thereby afford oscillating movement of the device at right angles to said plane; means for effecting intermittent revolution of said disk to register different striker parts with said guides and for imparting alternate oscillating movement to said device; and plungers

in said guides with which the striker parts on said disk come into contact when said device is moved in one direction, and a sound producing organism actuated by said plungers to render a tune according to the arrangement of said striker parts on the disk.

8. In a toy player piano having the usual bank of keys and adapted to be operated by a revolvable disk having striker parts arranged in circles of different radii, the combination with such a disk, of a device adapted to support the disk for rotation, a plurality of elements coinciding in position with said circles and arranged for registration with successive striker parts as the disk is revolved, the plane of rotation of the disk when supported by the aforesaid device being such that said striker parts escape operative engagement with said elements, said device being mounted for to-and-fro movement at substantially right angles to the plane of the disk so as to cause the striker parts to engage and operate the elements, and means for effecting intermittent rotation of said disk to register different striker parts with certain ones of said elements and alternately imparting to-and-fro movement to said device, the aforesaid elements having operative connection with the keys of the piano.

9. The combination defined by claim 8, wherein in said device is provided with a pocket in which the disk is peripherally supported for rotation.

10. The combination according to claim 9, wherein said pocket is defined by said guides and a bottom support, and between and upon which, respectively, the disk is guided and supported for rotation.

11. In a toy player piano adapted to be operated by a revolvable disk having striker parts arranged in circles of different radii, the combination with said disk, of a device adapted to support the disk for rotation and having openings coinciding with said circles whereby to align successive striker parts with said openings as the disk is rotated, said device being pivotally mounted for oscillating movement about an axis extending substantially parallel to the plane of the disk, continuously rotatable means for effecting intermittent partial rotation of said disk to align different striker parts with said openings and for alternately imparting oscillating movement to said device; plungers disposed adjacent the openings and actuated by the striker parts of the disk when the device is moved in one direction, and operative connections between said plungers and the keys of the piano.

12. In a toy player piano, a bank of keys, a series of hammers, one hammer operatively connected to each key, a disk having striker parts arranged in circles of different radii, a device adapted to support the disk for rotation and having openings coinciding with the different circles for registering successive striker parts with said openings as the disk is revolved, a sound bar secured to the lower portion of said device, tone rods of graduated lengths secured at their lower ends to said sound bar and projecting upwardly in closely spaced relation to said device and in operative relation to the aforesaid hammers, said device being pivotally mounted for oscillating movement about an axis extending substantially parallel with the plane of the disk, means for effecting intermittent rotation of said disk to register different striker parts with the openings and for alternately imparting oscillating movement to said device, actuators disposed adjacent the openings so as to be engaged and moved by

the striker parts on the disk when the device is swung in one direction, and operative connections between said actuators and the keys of the piano.

13. In a toy player piano, a casing including end walls, and parts extending between and connecting together said end walls, a bank of keys and associated hammers pivotally supported within the casing, each hammer being operatively connected to a key, an assembly including a back wall and a relatively heavy sound bar extending along the bottom of the back wall and secured to the inner side thereof, pivotal connections between said assembly and the end walls in the region of the front of said sound bar, whereby said assembly tends to overbalance rearwardly, a stop limiting the rearward movement of said assembly, means on the rear side of the back wall for peripherally supporting a disk for rotation in a plane substantially parallel to that of the back wall, a disk adapted to be supported by said means and having striker parts arranged in circular courses of different radii that are substantially concentric with the axis of rotation of the disk, the back wall having guide means that coincide with the aforesaid courses, actuators sustained by said guide means in operative relation to the striker parts of the disk, said actuators having operative connection with the keys, and means for imparting intermittent partial rotation to the disk and alternate oscillatory movement to said assembly.

14. A toy player piano according to claim 13, wherein the disk is provided with substantially equally spaced apart peripheral driving portions, and the means for rotating the disk and oscillating said assembly consists of a shaft rotatably supported at its forward end by a part of the casing and at its rear end by the back wall, the shaft extending forwardly beyond said part of the casing and rearwardly beyond said back wall, a crank or its equivalent secured to the front end of the shaft, and a cross arm fastened to the rear end of the shaft and having at one end a part for cooperation with the driving portions of the disk and at its other end a cam engaging element, and a cam on the back wall in the path of said cam engaging element.

15. A toy player piano according to claim 13, wherein the disk supporting means includes side guides between which the disk is adapted to be disposed, and a cross member extending from one side guide to the other in substantially parallel spaced relation to the back wall, and a support carried by the rear side of the back wall on which the disk rests.

16. In a toy player piano, a casing including end walls, a top wall and a front wall; a closure hingedly connected to the rear edge of the top wall and adapted to be swung between a closed position in the plane of said top wall and an open position overlying the top wall, an assembly including a back wall pivotally connected to the

end walls on an axis parallel with the back wall and forwardly thereof, a relatively heavy sound bar secured to the inner side of the back wall adjacent its lower edge, tone rods carried by and rising from the sound bar and graduated in length to produce different tones, a bank of keys pivotally supported in the casing, hammers operatively connected to the keys and disposed in operative relation to the tone rods, a number of disks, each characterized by a plurality of striker parts arranged according to the tune to be played by said disk and in circular courses of different radii, means incorporated in said assembly and so related to the back wall as to provide an upwardly opening pocket in which a disk may be deposited when the aforesaid closure is in open position and wherein the disk will be supported with its upper portion exposed above the top of the piano, and means for imparting to a disk deposited in said pocket intermittent partial rotation, and for alternately oscillating said assembly, guide means incorporated in the assembly that coincide with the aforesaid circular courses, actuators movably sustained by said guide means in a position to be engaged by said striker parts as the disk is rotated, and operative connections between said actuators and the keys.

17. The combination defined by claim 16, wherein the musical score of the tune to be played by each disk is carried by and extends circumferentially of the front surface of the disk adjacent the periphery thereof.

18. In a toy piano according to claim 16, wherein each disk is provided with substantially equally spaced peripheral driving parts, and the mechanism for rotating the disk and imparting oscillatory movement to said assembly consists of a shaft extending fore and aft through the casing and rotatably supported near its ends by the front and back walls of the casing, a crank secured to the front end of the shaft, a coil spring surrounding the shaft and interposed between the crank and the front wall of the casing, a member fastened to the rear end of the shaft and including a finger for cooperation with the driving parts of the disk, a cam engaging element incorporated in said member, and a cam on the back wall that is intermittently engaged by said element as the shaft is rotated.
